TOY WHISTLE OR SIMILAR ARTICLE

Sammy S. Wechsler, New York, N. Y.

Application February 23, 1955, Serial No. 34,633

Term of patent 3½ years

(Cl. D34—15)

FIG. 2

Fig. 1 is a side elevational view of a toy whistle or similar article, showing my new design, the opposite side having substantially the same appearance; and

Fig. 2 is an end view thereof.

I claim:

The ornamental design for a toy whistle or similar article, as shown and described.
